UNITED STATES PATENT OFFICE.

THOMAS LAMB, OF BROOKLYN, NEW YORK.

ANTISEPTIC PROTECTOR.

1,104,908.

Specification of Letters Patent. Patented July 28, 1914.

Application filed December 9, 1912. Serial No. 735,769.

To all whom it may concern:

Be it known that I, THOMAS LAMB, a citizen of the United States, residing at Brooklyn, in the county of Kings and State of New York, have invented certain new and useful Improvements in Antiseptic Protectors, of which the following is a specification, reference being had therein to the accompanying drawing.

10 This invention relates to telephone attachments and more particularly to antiseptic protectors adapted to be attached to the transmitter of a telephone.

The primary object of the invention is the provision of an improved device of the character stated possessing the characteristics of simplicity, cheapness, and efficiency.

The preferred embodiment of the invention comprises a device capable of attachment to either the transmitter or receiver of a telephone; and embracing novel features of construction enabling attachment and detachment of the device relative to the transmitter or receiver, as the case may be.

25 A further object of the invention is the provision, in a device of the character specified, of a supplemental mouth-piece or cup for the receiver or transmitter, adapted to support the attaching means and the disinfectant material; and the same combined with a closure for the said supplemental mouth-piece or cup when not in use; and still more specifically the closure being formed detachable and so shaped as to constitute a cover for the free ear of the person using the telephone.

The foregoing and other advantageous details in the construction and arrangement of parts constituting the preferred embodiment 40 of the invention to which I have alluded, will be apparent from the specific description hereinafter contained when read in connection with the accompanying drawings forming part hereof and wherein said embodiment of the invention is illustrated.

In the drawings, Figure 1 is a rear view of the attachment. Fig. 2 is a front view. Fig. 3 is a side elevation. Fig. 4 is a side elevation of the parts in separated relation.

50 Referring more specifically to the drawings, wherein like reference characters designate corresponding parts in the several views, A represents a supplemental mouth-piece or cup, the same being provided with a removable cover B adapted normally to

close the same and when removed to constitute a cover for the free ear of the user of the telephone, useful in many instances where the user is surrounded by disturbances tending to interfere with the hearing. The 60 back C of the cup A just referred to is formed with a central opening D adapted to register with the opening in the ordinary telephone mouth-piece or receiver, and either on the inside or outside (or both), of 65 this back, are laid sheets or pads E of medicated material such as tissue paper, constituting the vehicle for carrying the antiseptic or disinfecting substance. These sheets E are detachably secured in place by means of 70 headed studs F, F', the same being four in number, passed through the sheets and through key hole slots G in the back C. The studs F are carried at the opposite ends of an elongated plate H, having a central opening h registering with the opening D in the back, this plate carrying outwardly projecting, oppositely disposed wire loops J, curved inwardly at their ends, adapted to receive within the same the enlarged end of the 75 usual telephone receiver, the loops J being adapted to be sprung over said end so as to receive and embrace the same to support the attachment on the receiver when that use of the attachment is desired. The other pair 80 of studs F' are carried by a similar plate K arranged at right angles to the plate H and overlying the same, this plate J being also provided with a central opening k registering with the corresponding openings in the 85 plate J and back C. The plate K carries an arched wire rest L spaced a substantial distance therefrom adapted to engage and receive within the space between the arched portion and the plate, the mouth-piece of 90 the ordinary transmitter, when supporting the device on said transmitter. The two plates being arranged as described, together constitute a substantially continuous disk behind the back C to confine therebetween 95 the tissue paper or similar sheets E, the latter bridging the opening in the plates and back, and the two pairs of studs carried by the two plates constitute a four-point fastening engagement between the parts to securely hold the same in place, while permitting easy detachment of either or both of the plates, and the changing of the disinfecting material at will.

100 While I have herein illustrated one em- 110

bodiment of the invention, it will be understood by persons skilled in the art, that the invention is capable of being embodied in forms and devices other than that especially described, for the purpose of according a clear understanding of the invention desired to be protected.

I claim:

1. An anti-septic protector for telephones comprising a supplemental mouth-piece or cup having its flange disposed forwardly, means extending rearwardly from the cup enabling attachment of the same to a telephone in the normal condition of the latter, and an anti-septic vehicle on the back of the cup interposed between the same and said means, and engaged to be held in place by the latter, substantially as described.
2. An anti-septic protector for telephones comprising an anti-septic vehicle, devices enabling attachment of the same to a telephone transmitter, and other devices enabling the attachment thereof to a telephone receiver, said devices being crossed and provided with means at the opposite ends thereof coöperating with each other to support the anti-septic vehicle.
3. An anti-septic protector for telephones comprising a supplemental mouth-piece or cup, an anti-septic vehicle carried thereby, and means enabling attachment of the same to a telephone, said means comprising a plate carrying headed studs, and the back of the mouth-piece or cup having key-hole slots for engagement with said studs.
4. An anti-septic protector for telephones comprising a supplemental mouth-piece or cup, an anti-septic vehicle carried thereby, and means enabling attachment of the same to a telephone, said means comprising a plate carrying headed studs, and the back of the mouth-piece or cup having key-hole slots for engagement with said studs, the anti-septic vehicle being also engaged by said studs.
5. An anti-septic protector for telephones comprising a supplemental mouth-piece or cup having its flange disposed forwardly, means extending rearwardly from the cup enabling attachment of the same to a telephone in the normal condition of the latter, an anti-septic vehicle on the back of the cup interposed between the same and said means, and engaged to be held in place by the latter, and a detachable cover for said anti-septic vehicle adapted to normally protect the same, said cover being formed to constitute, when removed, a cover for the ear of the user, substantially as described.
6. An anti-septic protector for telephones comprising a supplemental hollow mouth-piece or cup, an anti-septic vehicle carried thereby, means enabling attachment of the same to a telephone, and a detachable cover for the hollow mouth-piece or cup for nor-

mally protecting the interior of the same, formed when removed to constitute a covering for the ear of the user.

7. An antiseptic protector for telephones, comprising a vehicle for the antiseptic substance, and means for supporting the same on the transmitter of a telephone comprising a plate and an arched rest adapted to receive the upper half of the transmitter mouth-piece, open at its bottom to permit free entrance of said mouth-piece thereto, and separated from said plate by terminal portions connecting the arched rest to the plate so as to accommodate the mouth-piece between said arched rest and the plate, substantially as described.

8. An antiseptic protector for telephones, comprising a vehicle for the antiseptic substance, means for supporting the same on the transmitter of a telephone comprising a plate and a substantially semi-circular open arched rest of permanent formation separated from said plate adapted to engage the transmitter circumferentially of the latter and to receive the same between said arched rest and the plate, and means on said plate detachably engaging the vehicle for the antiseptic substance, substantially as described.

9. An antiseptic protector for telephones comprising a vehicle for the antiseptic substance, and means for supporting the same comprising oppositely disposed spring metal members having engaging portions separated by open spaces adapted to detachably embrace and engage at two points correspondingly opposite portions of the telephone receiver, a plate carrying said members, and means on the plate for engaging the vehicle for the antiseptic substance, substantially as described.

10. An antiseptic protector for telephones comprising a vehicle for the antiseptic substance, and means for supporting the same comprising oppositely disposed elongated open wire loops adapted to be forced apart by the telephone receiver when detachably engaging the latter, the open spaces in the loops accommodating peripherally projecting portions of the receiver, substantially as described.

11. An antiseptic protector for telephones comprising a vehicle for the antiseptic substance, and means for supporting the same comprising oppositely disposed elongated open wire loops adapted to be forced apart by the telephone receiver when detachably engaging the latter, the open spaces in the loops accommodating peripherally projecting portions of the receiver, said loops being curved so that the ends thereof will relatively diverge in an inward direction.

12. An antiseptic protector for telephones comprising a supplemental mouth-piece or cup, a vehicle for antiseptic material asso-

ciated therewith, said mouth-piece or cup having key-hole slots in its back, superposed plates arranged at right angles to each other on the back of the mouth-piece or cup, 5 headed studs at the ends of the plates engaging the key-hole slots in the back, and supporting devices respectively carried by the plates adapted to engage a telephone receiver and transmitter, substantially as de-
10 scribed.

13. An antiseptic protector for telephones comprising a supplemental mouth-piece or cup, a vehicle for antiseptic material associated therewith, said mouth-piece or cup 15 having key-hole slots in its back, superposed

plates arranged at right angles to each other on the back of the mouth-piece or cup, headed studs at the ends of the plates engaging the key-hole slots in the back and supporting devices respectively carried by 20 the plates, the headed studs also engaging the vehicle for the antiseptic substance to secure the same in place.

In testimony whereof I affix my signature in presence of two witnesses.
